(57) **CLAIM**

The ornamental design for a combined insect lure and fish feeder, as shown and described.

DESCRIPTION

FIG. 1 is a perspective view of an combined insect lure and fish feeder;

FIG. 2 is a side elevational view thereof, all sides being identical;

FIG. 3 is a top plan view thereof; and,

FIG. 4 is a bottom plan view thereof.

Throughout the figures broken lines are for purposes of illustration only and are not part of the claimed design. The break lines being shown in FIGS. 1 and 2 to indicate indeterminate length.
